Application June 26, 1956, Serial No. 593,981

3 Claims. (Cl. 33—9)

This invention relates to skirt markers such as are used by women to mark the desired position of the height of the bottom edge of their skirts from the floor, or of the height from the floor to the top of the hem of the skirts. Various devices have been made available for this purpose, of which some are height indicators showing where pins must be inserted to mark where the skirt must be sewed, but the disadvantage of this is that the wearer of the skirt being so marked cannot also do the marking. Another type of marker has been marketed whereby chalk is blown against the skirt but here the mark has not been too distinct, or has been interrupted, or the operation in general has not been satisfactory.

So it is an object of this invention to overcome these disadvantages and to devise a skirt marker that can be operated by the wearer of the skirt, that is simple in all of its operations so that even the height adjustment can be made by a person with no mechanical aptitude; and that makes a chalk mark wide enough when applied so as to be distinct and due to its width, the wearer of the skirt can turn around wiping the skirt past the chalk marker at a fairly rapid rate.

With these objectives in mind, the invention may be said to be realizable by a base having an upstanding skirt guide rising from one edge of the base and from the other edge an upstanding standard carrying a measuring scale, while vertically adjustable thereon is an assembly including a nozzle-bearing chalk-blowing casing having connected thereto a tube with a air-pumping compressible bulb on its free end, and with the tube long enough to reach to the hand of the woman who is marking her skirt. Details from which advantages flow comprise the particular shape of the nozzle member that is generally keyhole in shape having a space below for receiving chalk from its cup, with the particular pathway through which the air comes into the member and leaves therefrom with the chalk suspended therein in a stream that is progressively thinned but progressively widened.

The invention is illustrated in the accompanying drawings in which Figure 1 is an isometric view of the complete skirt marker. Fig. 2 is a plan view, with parts in section of the chalk blower. Fig. 3 is a vertical sectional view through the chalk blower.

In the drawings, there is shown a base 11 from the front edge of which rises an upstanding skirt guide 12 to a height substantially co-equal with that of a standard 13, more or less rectangular in cross-section but having inturned edge flanges 14 and 16 forming channels 15 and 17 between which is frictionally gripped a transversely curved ruler or face plate 18 preferably of metal, bearing a scale of measuring numerals 19 indicating the height from the floor. 20 indicates a top cover or cap for the standard 13.

Adjustably and vertically slidably held in channels 15 and 17 by friction against the inturned flanges 14 and 16 as a result of the convexly bowed spring face plate 18, is a much shorter plate 22 whose lateral edges 23 and 24 enter the channels 15 and 17, respectively. This shorter

2

plate has secured thereto an assembly shown generally at A for blowing powdered chalk against the skirt that is to be marked. The chalk blower assembly comprises a generally cylindrical hollow casing 26 open at its bottom 5 for the reception of an open-topped cup 27 adapted to hold a quantity of powdered chalk 28. The bottom of the cup projects below the bottom of the casing 26 so the cup can be readily removed and replaced to be refilled or replenished from time to time with powdered chalk. The 10 interior of the casing 26 is provided with an annular shoulder or seat 29 against which the cup can be seated. Above the annular shoulder 29 is a space 30 within a horizontal nozzle member N which latter has in plan view the shape of a keyhole, with a top plate 37, a bottom plate 31, a cylindrical portion 32 and an outwardly flared portion 33, terminating in a chalk-spraying elongated terminal outlet or nozzle 34. The outlet has a plurality of partial partition walls 35 and 36, while the bottom 31 of the nozzle member is inclined upwardly toward 15 the outlet 34 for progressively thinning the space between the top 37 and bottom 31. And the top of the nozzle member N is closed by the frictionally-held but removable top cover plate 37, having marginal flanges 38 and 39. Through the top cover plate 37 there extends a tubular connection 40 to which is secured a flexible hose 20 leading to a compressible pressure-inducing bulb 42, such as of rubber. The neck portion 43 between the cylindrical portion 32 and the nozzle member N has a functional purpose of controlling the flow of blown chalk in a particular manner.

In operation, the person whose skirt is to be marked, stands so that the skirt hangs between the skirt guide 12 and the chalk blower assembly 25. The chalk blower assembly is then adjusted to the proper height at which 25 the skirt is to be marked, by sliding the plate 22 up or down in the channels 15 and 17. The proper adjustment as to height is measured by comparing either the top edge of the plate 22 or its bottom edge, against the numerals 19 on the face plate 18. These numerals can 30 be so imprinted on the face plate that one or the other of these edges is correctly measured, or, indeed, the plate 22 can be of transparent plastic so the numerals can be seen therethrough and the blower nozzle 34 adjusted to the right numeral. The cup 27 is removed from the cylinder 26, and after being filled with powdered chalk 28 is replaced, as shown. Next, the operator pumps the bulb 42 which supplies pressured air through the tube 41 into the space 30, which air descends into the powdered chalk to stir it up vertically and blow it horizontally through 35 the nozzle 34 from which it is emitted in uniformly dispersed form due to the spreading effect of the partial partitions 35 and 36. The tube 40 is aligned with the rear of the cup 27 so that the path of the descending air passes directly down into the chalk as shown in Fig. 3, turns and then blows the chalk first vertically upwardly and then horizontally where it is somewhat condensed as it passes through the neck portion 43 before it spreads out laterally in passing through and outwardly from the nozzle, meanwhile spreading out laterally in a progressively 40 thinning but broadening stream. The outwardly flared portion 33 of the nozzle sprays the chalk in a line of considerable lateral extent. The woman stands with her skirt between the upstanding guide 12 and the scale 18 while the chalk blower is directed toward the skirt. 45 Chalk blown from the nozzle of the chalk-blowing assembly is caught by the skirt since the guide keeps the skirt from being blown too far away from the chalk-blowing nozzle. The woman turns while the chalk continues to be blown or sprayed until a chalk line is made 50 that encircles the skirt.

There has thus been devised a skirt marker that requires a minimum of mechanical skill to operate; that is

easily adjusted to the proper height; that retains its adjusted height; that blows a stream of powdered chalk along a horizontal line of considerable lateral extent; that blows the powdered chalk while uniformly dispersed in a lateral direction; and a chalk-blowing assembly that is easily taken apart for inspection.

We claim:

1. A skirt marker of the powdered chalk-blowing kind, having a base, a standard rising from said base and to constitute a post providing height-indicating graduations, a carrier bracket being vertically adjustable upon said post and frictionally held thereon at any adjusted elevation and bearing a powdered chalk marker head with chalk blowing nozzle adapted to emit a chalk-marking air stream horizontally away from said post at an elevation identifiable by said graduations, said post being in the form of a vertical shell profiled to comprise a vertical flat body portion, a pair of longitudinal side portions each providing an inwardly directed overhanging vertical flange to constitute with the body portion a vertical groove so that the grooves face inwardly toward each other, and a graduated vertical face plate representing a scale of convexly shaped cross-section edgewise in said vertical grooves, said carrier bracket comprising a plate substantially conforming to the curvature of said face plate and held edgewise frictionally although slidably in said grooves for sliding adjustment vertically along said scale.

2. The marking head according to claim 1, in which said nozzle in plan view has a flaring configuration constituting substantially a keyhole shape.

3. A skirt hem marker having a base, a standard rising from the base to constitute a post, and a marking head with a supporting bracket vertically adjustable upon said

post and cooperative therewith in fixing the distance of the hem to be marked from the ground; characterized thereby that said post comprises a vertical longitudinal shell cross-sectionally profiled to constitute an intermediate longitudinal flat body portion, a pair of longitudinal side portions each in the form of an inturned flange spaced from the body portion to constitute therewith a longitudinal groove, so that said grooves face inwardly toward each other, a graduated longitudinal face plate in the nature of a scale of shallow convexity in cross-section and held longitudinally edgewise in and by said grooves; and that said bracket and adjusting means are in the form of a plate curved substantially to conform to said convexity and slidably superimposed upon said scale and frictionally held along its longitudinal edges in and by said grooves in any desired vertically adjusted position along said scale.
